UNITED STATES PATENT OFFICE.

JOSEPH LEONARD, OF ALLENTOWN, PENNSYLVANIA, ASSIGNOR TO FIFTH AVENUE CORSET COMPANY, INC., OF ALLENTOWN, PENNSYLVANIA, A CORPORATION OF NEW YORK.

CORSET.

Application filed January 13, 1923. Serial No. 612,413.

To all whom it may concern:

Be it known that I, JOSEPH LEONARD, a citizen of the United States of America, and a resident of the city of Allentown, county 5 of Lehigh, and State of Pennsylvania, have invented certain new and useful Improvements in Corsets, of which the following is a specification.

The object of this invention is to provide 10 a garment which combines the usual function of a corset with an abdominal belt so that it can be put on or taken off as a single garment. Further objects are to provide both vertical and lateral adjustments for the 15 abdominal belt in relation to the corset proper. Further objects are to provide adjustments which adapt it to varying dimensions over the thighs and around the hips independently of adjustments at the waist and 20 above the waist. Further objects are to provide for access from the outside and while the corset is being worn in making such adjustments. Also the construction is such that in making these adjustments the puckering or wrinkling of any part will be avoided. 25 Also these features are such that they may be embodied either in a corset with bones or in a corset brassière without bones, and either of which may be either front opening or rear opening and may or may not be extended above the waist to support the bust.

In the accompanying four sheets of drawings which forms a part of this specification, 30 Figure 1 is a general view showing a corset brassière in which the invention is embodied.

Fig. 2 shows the brassière opened and laid out flat.

Fig. 3 is a general view showing a corset in which the invention is embodied.

Fig. 4 shows the corset opened and laid out flat.

In the embodiment in a brassière, a soft 45 fabric outer portion 10 completely encircles the body. It is made up of several sections which are united by vertical lines of stitches 11, 11, and the lines of stitches may be protected with tapes 12, 12 on the inner side. 50 The brassière as shown is continuous across the front and opens at the middle of the back where it is connected by a line of hooks and eyes 13, 13. Where the brassière comes at the sides of the body it is split up to the 55 waist line W—L and the adjacent edges on

each side of the splits are provided with eyelets 14, 14 for side lacing connections 15, 15. Elastic sections 16, 16 overlie the upper edges of the split sides and are connected at their ends by vertical lines of stitches but they are 60 not stitched along their lower edges to the parts which carry the eyelets. The adjacent edges on each side of the splits may be separated or drawn close together by the lacing as needed for a proper fit and such adjustments will not pucker the parts of the outer portion above the splits because of the elastic sections. Flaps 17, 17 underlie the side lacing. Elastic thigh sections 18, 18 are set in the front adjoining the lower ends of the 70 splits to provide necessary yielding points when the wearer is seated and permit a corset which is designed to fit the body at a lower point.

An abdominal belt 20 has eyeleted ends 21, 21 which are narrower than the lengths of the side lacing connections and these ends are connected with the side lacing connections at such points higher up or lower down as is found most suited 80 to the wearer since it is connected with the outer portion only through the lacing connections. Its length is the same as the width of the front of the outer portion and in drawing up and adjusting at the sides 85 they will be drawn tight together and without wrinkling of either. The lower edge of the abdominal belt is higher up than the lower edges of the elastic thigh sections so that it does not underlie these sections or 90 underlies them but partially and will not interfere with their properly yielding to permit the wearer to sit comfortably.

In the embodiment in a corset, as shown, 95 the corset proper 25 is continuous across the back except that an elastic section 26 is set in along the middle of the back. The corset completely encircles the body and opens in front where it is connected by a line of hooks and eyes. The parts heretofore described in connection with the brassière function in the same manner and the same reference numerals are applied. The abdominal belt, however, on account of the front opening is separable along one side 100 and is in two parts 27, 28 connected by lines of hooks and eyes 29, 29 so that connecting and separating may be quickly made here in putting on or taking off the corset and the adjustment at the lacing connec- 105 110

tions need not be disturbed. Furthermore the splits at the sides of the corset extend through to the top thereof, the upper elastic portions and the lacing being the only side connection at the bust.

The nature of the outer portion, and whether it is a brassière without bones or a corset with bones is immaterial to this invention and the term corset is to be understood as a generic term covering both the brassière and corset proper.

The foregoing detailed description has been given for clearness of understanding only, and no undue limitation should be deduced therefrom, but the appended claims should be construed as broadly as permissible in view of the prior art.

I claim:

1. A corset which completely encircles the body and is split at the sides below the waist line, side lacings connecting the adjacent edges of the split sides together and an abdominal belt terminating at its ends adjacent the side splits and connected at its ends to the said side lacings.

2. A corset which completely encircles the body and is split at the sides below the waist line, side lacings connecting the adjacent edges of the split sides together, flaps underlying the side lacings, and an abdominal belt connected at its ends to the said side lacings.

3. A corset which completely encircles the body and is split at the sides below the waist line, side lacings connecting the ad-

jacent edges of the split sides together, and an abdominal belt terminating at its ends adjacent the side splits and connected at its ends to the said side lacings, the ends of the belt being narrower than the lengths of the side lacing connections whereby the belt may be vertically shifted.

4. A corset which completely encircles the body and is split at the sides below the waist line, side lacing connections at the adjacent edges of the split sides and elastic sections which overlie the upper ends of the split sides and the upper portions of the said side lacing connections.

5. A corset which completely encircles the body and is split at the sides below the waist line, elastic thigh sections in the front adjacent the lower edges of the split sides and terminating at their outer ends adjacent the side splits, and lacings connecting the adjacent edges of the split sides together and to which the outer ends of the elastic thigh sections are connected.

6. A corset which completely encircles the body and is split at the sides below the waist line, side lacing connections at the adjacent edges of the split sides, and elastic sections which overlie the upper ends of the split sides and the upper portions of the said side lacing connections, the portions of the corset above the elastic sections being inelastic.

Signed at New York, N. Y., this 11th, day of January, 1923.

JOSEPH LEONARD.
